UNITED STATES PATENT OFFICE

2,206,051

DOUBLE-DOOR-OPERATING DEVICE

Ralph H. Roof, Tulsa, Okla.

Application September 6, 1938, Serial No. 228,570

7 Claims. (Cl. 268—62)

This invention relates to a door operating mechanism constructed to aid in the opening and closing of double hung doors such as used on garages and various other buildings and it consists in the novel construction and combination of the parts hereinafter fully described and claimed whereby, when used in combination with a pair of hingedly supported doors, both doors are retained in a closed position; opened and closed simultaneously; limited in their opening movement; held securely open until released and permits the partial opening of one door without transmitting opening movement to the other door.

The objects of the present invention are: to generally improve and simplify, by novel construction and new combinations of various elements used in door operating devices, the construction and operation of door operating mechanism of the character described; to provide a door operating mechanism particularly intended for application to double hung garage doors and the like; to provide a door operating mechanism which can be quickly and readily applied to garage doors and which is adjustable to take care of doors of varying width; to provide a door operating mechanism which retains both doors in a closed position, embodying in the retaining element features of construction which in combination with other elements of the device permits adjustment to be made whereby the proper amount of pressure necessary to retain said doors in a closed position may be regulated to suit varying conditions, thus causing said mechanism to function properly regardless of whether the doors on which the device is installed are heavy or light, exposed to strong winds or in protected areas; to provide a door operating mechanism which operatively connects both doors but permits partial opening of one door without transmitting opening movement to the other door; to provide a door operating mechanism which operatively connects both doors so that the opening of one door will be transmitted to open the other door and vice versa, embodying in the connecting element means for making possible the regulating of the pressure for retaining said doors in a closed position and the elimination of parts and simplifying of the means necessary to limit the doors in their opening movement and causing a holding element to automatically come into holding effect, simultaneously with the doors having reached the extent of their opening movement,

so that they will not accidentally close due to faulty hanging, wind puffs or otherwise, thereby eliminating any element of danger either to the doors, machines or persons when entering or leaving a building; to provide a door operating mechanism with means of adjustment, whereby the device may be set, so that the mechanism will function to limit the doors in their outward swing and hold same in a predetermined position with respect to the door opening; to provide a door operating mechanism of such construction that the vibrations caused by the opening and closing movement of the doors will be absorbed by the mechanism without harmful results to the building, the doors or the mechanism.

With the above objects in view, the invention resides in the combination and arrangement of parts and in the details of construction hereinafter described and claimed, it being understood that changes in the precise embodiment of the invention herein disclosed can be made within the scope of what is claimed without departing from the spirit of the invention.

The door operating mechanism is shown by way of illustration in the accompanying drawing, in which—

Fig. 1 is a plan view, partly in section and somewhat diagrammatic in character, of a door opening provided with double hung doors equipped with a door operating mechanism embodying the features of my invention.

Fig. 2 is a plan view showing one door partially open.

Fig. 3 is a perspective view generally on the line 3—3 of Fig. 1 and drawn to an enlarged scale illustrating features of operation.

Fig. 4 is a detailed cross section through one of the bracket members, the section being indicated by the line 4—4 of Fig. 1, and drawn to an enlarged scale illustrating features of construction.

Referring to the drawing in detail A, A indicates the main frame of a door on opposite sides of which is hung by hinges 1 and 2, a pair of doors generally indicated at B and C. Secured to the door B on the inside near the upper end thereof and adjacent the hinge is a bracket 5, which bracket is provided with an aperture for engagement, as at 18, with the end of a hollow rod 15, the same being in hinge connection with the aperture. The hollow rod 15 is in adjustable telescopic union with the rod 16, being held against telescopic movement by compressing the end of the hollow rod 15 at the point of engagement by means of a taper threaded collar, with

which hollow rod 15 is provided, as at 17, thus making it possible, by varying the point of engagement between hollow rod 15 and rod 16, to bring about an adjustment which regulates 5 the amount of compression that is to be applied to the spring 13, thereby controlling the force which retains the doors in a closed position, as hereinafter described, which is an advantage as doors vary in weight, and wind pressure in sheltered and unsheltered areas necessitates that 10 there be different adjustments. With this type of construction the amount of tension needed on said spring, to insure proper operation of the mechanism, does not depend on the original installation but may be adjusted after installation which is an advantage. Other advantages 15 are: it does not depend on the rigidity of its members to accomplish the action necessary to hold the doors in a closed position; it gives a 20 more flexible action and does not impose a strain on the mechanism, the doors or the building as do operating devices which depend on the rigidity of their members to accomplish this result. The opposite end of the rod 16 is in sliding 25 engagement with a crosshead 14, said sliding movement being limited by collars 11 and 11' and in opposition to spring 13, with which rod 16 is provided. Said collars being positioned on said rod in such a manner as to provide 30 enough tension on said spring to prevent any sliding action on the part of the rod 16 and crosshead 14 from taking place except in the partial opening or complete closing of door C, said collars being retained in said position by 35 rivets 12 and 12'. Crosshead 14 is pivotally secured to a bracket 6 as at 19 and is of such construction that support is applied to the rod 16 on both sides of the pivot point 19 which is an 40 advantage as this type of construction eliminates any tendency on the part of the connecting members to buckle or bind as would be the case should the sliding action of a compressible member occur in the connecting link intermediate the 45 brackets supporting said connecting link. Bracket 6 is secured to the inside of door C being positioned comparatively far or inward from the hinge 2 of the door C. Secured to the bracket 5 and being in hinge connection as at 25 is a link 27. Said link being provided with an upturned end as at 29 and pivotally engaged with link 28 as at 21. Link 28 is provided with a recess 9 for reception of upturned end 20 of link 27. The opposite end of link 28 is in pivotal connection as at 8 with a connecting member 10 with which hollow rod 15 is provided. The 55 position of said connecting member on said hollow rod is adjustable and retained in correct position by bolts 7 and 7' with which said connecting member is provided. Secured to links 27 and 28 as at 3 and 4 is a spring 22. Secured to link 27 as at 23 is a cord 31, the opposite end of said cord being secured to door B as at 24. Links 27 and 28 and their appertaining parts 60 comprise the limiting and holding element 65 whereby the doors are limited in their outward swing and held in open position until released. The spring 22 being of sufficient strength to retain the mechanism in holding effect until released by pulling the cord 31 as hereinafter described.

The mechanism as illustrated is simple and substantial in construction and can be readily applied to garage doors or the like in a comparatively short time as it is only necessary to secure the brackets 5 and 6 to the doors, by means of

bolts or screws such as shown in Fig. 3 and Fig. 4; to adjust the link comprising the sections 15 and 16 which takes care of varying width of doors, and regulates the tension on the compression spring 13, which retains the doors in a closed position, and adjust the limiting and holding mechanism, comprising the links 27 and 28 and their appertaining parts, whereby both doors are limited in their opening movement and held open at predetermined angles with respect to the door 10 opening. With the mechanism installed as described, the operation will be as follows:

Referring to the full lines of Fig. 1 of the drawing it is obvious that both doors are constrained to remain in a closed position, due to the spring 15 13 exerting a force in opposite directions, on the brackets 5 and 6, said force being applied in part to the crosshead 14 which is carried by bracket 6, said bracket being secured to door C and positioned inside of an imaginary dead center as at 20 29, thus exerting an inward pull on door C. Simultaneously there is exerted an equivalent force on bracket 5, by means of the connecting link 15 and 16, which causes an inward pull on door B. This force, due to spring 13, remains constant as 25 long as the doors are in a closed position. Should one find after installation of a device of this description, that it does not function properly in regard to holding the doors closed, because of the improper location of the brackets or as a 30 result of wear on the part of the door hinges or the mechanism or due to the spring 13 becoming weak, due to use, compensation may be made which will result in the proper operation of the mechanism by loosening the collar 17 which holds 35 the connecting link against telescopic movement, and lengthen or shorten the link composed of the rods 15 and 16, thereby applying more or less compression, as may be needed, to the spring 13. The same adjustment would be necessary in regard to light or heavy doors.

If it is desired to merely afford ingress and egress to a person, door C is swung from the full line position indicated in Fig. 1 at C to the full line position indicated in Fig. 2 at C. This action 45 is effected in opposition to the spring 13 until the link comprised of the parts 15 and 16 reaches a dead center position, as indicated in Fig. 2 at 29, with relation to the hinge axis of door C and pivot 19 of bracket 6. With the parts in this 50 position the operator will now exert a slight manual force upon door C in an outward direction so as to cause the pivot 19 to pass the dead center position and simultaneously with the passing of said dead center position the spring 13 will exert its force to cause an outward movement of door C, said force existing until collar 11' is brought 55 against crosshead 14 as in Fig. 2. Simultaneously with this movement door C will have moved to the position indicated at C in Fig. 2, thereby providing ample space for one or more persons to enter or leave the garage without opening the other door. With the parts 11, 11', 13, 16 and 14 in this position, the combination of said parts 60 form an integral unit, said unit being free to pivot as at 19 in Fig. 2, spring 13 being of sufficient strength to retain said parts in specified positions until sufficient force is applied to the door to compress spring 13, said compression occurring only when it is desired to open doors from a fully 65 closed position or close doors from a partially or fully opened position.

If it is desired to open both doors, for instance when entering or leaving the garage with an automobile, door C is swung beyond the full line 70 75

position indicated at C in Fig. 2, to the open position as indicated by the dotted lines at C' in Fig. 1. In doing so the link comprising the members 15 and 16 will cause an outward pull upon door B whereby said door will swing on its hinges to the open position as shown by the dotted lines at B' in Fig. 1. As the doors are opened the links 27 and 28 are actuated by the bracket 5 and the connecting link 15 and 16 through the connecting member 10 and are made to straighten out and are forced past the dead center alignment or dead center of pivot 21 as in Fig. 3. In such position the upturned end 20 of link 27, functioning as a stop finger, engages the recess 9 of link 28 thereby limiting the swing of the doors and automatically comes into and remains in holding effect until the cord 31 is pulled by hand, in opposition to spring 22, to break the dead lock of links 27 and 28. The link comprised of the members 15 and 16 being sufficiently resilient to absorb the vibrations caused by said limiting and holding mechanism stopping the doors in their outward swing. Any tendency on the part of the limiting and holding mechanism to move out of holding effect due to vibrations occurring in the doors or the mechanism is counteracted by the spring 22. This is an advantage over so called springless type holders. Should the connecting member 10, with which hollow rod 15 is provided, be moved from its position as shown in the accompanying drawing to a point nearer the pivot 18, said movement being permitted by loosening the bolts 1 and 1' with which said connecting member is provided, it is obvious that the links 27 and 28 would limit and come into holding effect, as heretofore explained, only when the doors had completed enough travel in their opening movement to actuate the limiting and holding mechanism which would be at a different position than that shown in the accompanying drawing, namely after the doors had assumed an open position of a greater angle with respect to the door opening. Should the connecting member 10 be moved in the opposite direction the limiting and holding mechanism would come into effect sooner with regard to the opening movement of the doors, thus making it possible, by moving the connecting member back and forth on rod 15, to set the mechanism so as to locate the doors in their fully open position at different predetermined angles with respect to the door opening, which is an advantage as it is often necessary to stop doors at different angles due to their proximity to other doors or to other buildings. A limiting and holding mechanism of this type, in combination with a connecting link and brackets, automatically accomplishes the limiting and holding action of both doors simultaneously with the doors reaching their open position through the operation of one door manually, which is an advantage. It is a further advantage over devices which use so called chain bolts or head and foot bolts for accomplishing the holding action as swaging on the part of the doors will not prevent a device of this type from functioning properly.

When it is desired to close the doors the operator first exerts a pull on the cord 31 as in Fig. 3, in opposition to the spring 22, thus breaking the dead lock of the links 27 and 28. This allows the jointed ends to fold in to the position shown in Fig. 2, as the doors close, thereby permitting the doors to be returned to the position as indicated in Fig. 2 by applying pressure to either door. In doing so motion is transmitted through the link

composed of the parts 15 and 16 to the opposite door and they are both swung to said position. If by chance operator was applying force to door B, which is natural since the release for the limiting and holding mechanism is attached to door B, to complete the closing operator applies pressure to door C, in opposition to spring 13, until the link comprised of the parts 15 and 16 pass the dead center position as at 29 in Fig. 2. Simultaneously with the passing of the dead center position the spring 13 will effect an inward pull on the door C thereby completing the closing action.

From the foregoing description it is evident that the described mechanism not only affords convenient ingress and egress both for a person and a car but also, by limiting the doors in their outward swing and holding them in open position, prevents injury to a car such as not infrequently occurs when garage doors blow to or otherwise inopportune close. It is unnecessary to provide a set of doors equipped with this device with any latch, bolt or other mechanism for holding said doors in a closed position, unless it is desired to lock said doors in a closed position, in which case an ordinary hasp and padlock should be sufficient, thus eliminating cost of latches, etc.

While I have not shown it, it is obvious that I may add a weight, in which instance a cord or runner would be attached to the bracket 6, and the same would be trained over suitable pulleys with the weight at its free end in such manner that gravity would function to accomplish the closing action, once the mechanism for holding the doors in an open position was released. While I have described a weight for accomplishing these results, obviously, I may substitute its equivalent, a spring.

While the invention has been described in connection with garage doors it is obvious that it may be applied to double hung closures of any character.

Having thus described my invention, what I claim and desire to secure by Letters Patent is:

1. In a door operating mechanism the combination with a pair of hingedly supported doors adapted to normally close a door opening, a bracket secured to each door, two links hinged together, one end of one of said links pivoted to one of said brackets and with anchor members, a spring connected to each of said links, a cord connected to one of said links, a pivotal connection between the opposite end of said links and a connecting member connecting with an adjustable link, pivotally connecting said bracket and in pivot and sliding connection with the bracket on the other door, the last mentioned bracket having a crosshead assembled therein and provided with appertaining parts, namely, a spring and two collars, the link being of such length that the latter pivotal connection crosses the dead center line passing through the adjacent hinge and the other pivotal connection when the doors are opened or closed.

2. In a door operating mechanism the combination with a pair of hingedly supported doors adapted to normally close a door opening, a bracket secured to each door, two links hinged together, one end of one of said links pivoted to one of said brackets and, with anchor members, a spring connected to each of said links, a cord connected to one of said links, a pivotal connection between the opposite end of said links and a connecting member connecting with an

adjustable link, pivotally connecting said bracket and in sliding connection with a crosshead, said crosshead being in pivot connection with the bracket on the other door, said crosshead being provided with appertaining parts, namely, a spring and two collars, and arranged to prevent buckling on the part of said adjustable connecting link, the link being of such length that the latter pivotal connection crosses the dead center line passing through the adjacent hinge and the other pivotal connection when the doors are opened or closed and means on the last named bracket arranged to permit adjustment to be made whereby the proper force may be utilized 10 in maintaining both doors in a closed position.

3. In a door operating mechanism the combination with a pair of hingedly supported doors adapted to normally close a door opening, a bracket secured to each door, two links hinged together, one end of one of said links pivoted to one of said brackets and, with anchor members, a spring connected to each of said links, a cord connected to one of said links, a pivotal connection between the opposite end of said links and a connecting member connecting with an adjustable link, pivotally connecting said bracket and in pivot and sliding connection with the bracket on the other door, the last mentioned bracket having a cross head assembled therein and provided with 20 appertaining parts, namely, a spring and two collars, the link being of such length that the latter pivotal connection crosses the dead center line passing through the adjacent hinge and the other pivotal connection when the doors are opened or closed and the last mentioned bracket, crosshead assembly and appertaining parts so constructed as to permit a limited independent movement of the door about its hinges without transmitting movement to the opposite door.

4. In a door operating mechanism the combination with a pair of hingedly supported doors adapted to normally close a door opening, a bracket secured to each door, two links hinged together, one end of one of said links pivoted to one of said brackets and, with anchor members, a spring connected to each of said links, a cord connected to one of said links, a pivotal connection between the opposite end of said links and a connecting member connecting with an adjustable link pivotally connecting said bracket and in pivot and sliding connection with the bracket on the other door, the last mentioned bracket having a crosshead assembled therein and provided with appertaining parts, namely, a spring and two collars, the adjustable connecting link being of such length that the latter pivotal connection crosses the dead center line passing through the adjacent hinge and the other pivotal connection, when the doors are opened or closed, and which transmits opening movement of one door to the other and vice versa, and means on said adjustable connecting link, arranged to provide adjustment, whereby the amount of compression applied to the last mentioned spring, 55 with which said crosshead is provided, may be properly regulated.

5. In a door operating mechanism the combination with a pair of hingedly supported doors adapted to normally close a door opening, a bracket secured to each door, an adjustable link in pivot connection with one bracket and in pivot and sliding connection with the bracket on the other door, the last mentioned bracket having a crosshead assembled therein and provided with appertaining parts, namely, a spring and two collars, the link being of such length that the latter pivotal connection crosses the dead center line passing through the adjacent hinge and the other pivotal connection when the doors are opened or closed and means on the first named bracket and the connecting link for limiting the 15 doors in their opening movement and holding the doors in open position.

6. In a door operating mechanism the combination with a pair of hingedly supported doors adapted to normally close a door opening, a bracket secured to each door, two links hinged together, one end of one of said links pivoted to one of said brackets and, with anchor members, a spring connected to each of said links, a cord connected to one of said links, a pivotal connection between the opposite end of said links and a connecting member connecting with an adjustable link, pivotally connecting said bracket and in pivot and sliding connection with the bracket on the other door, the last mentioned bracket having a crosshead assembled therein and provided with appertaining parts, namely, a spring and two collars, the adjustable link being of such length that the latter pivotal connection crosses the dead center line passing through the adjacent hinge and the other pivotal connection when the doors are opened or closed and means on said connecting member whereby said connecting member may be moved along said adjustable link in setting the device so as to regulate the scope of the angular position that the doors may assume when in full open position.

7. In a door operating mechanism the combination with a pair of hingedly supported doors adapted to normally close a door opening, a bracket secured to each door, two links hinged together, one end of one of said links pivoted to one of said brackets and, with anchor members, a spring connected to each of said links, a cord connected to one of said links, a pivotal connection between the opposite end of said links and a connecting member connecting with an adjustable link, pivotally connecting said bracket and in pivot and sliding connection with the bracket on the other door, the last mentioned bracket having a crosshead assembled therein and provided with appertaining parts, namely, a spring and two collars, the adjustable link being of such length that the latter pivotal connection crosses the dead center line passing through the adjacent hinge and the other pivotal connection when the doors are opened or closed and the last mentioned link being resilient to absorb operating vibrations.

RALPH H. ROOF.
